UNITED STATES PATENT OFFICE.

EDWARD LUCIUS CUSHMAN, OF MIAMI, FLORIDA.

SLUG.

1,328,725.

Specification of Letters Patent. Patented Jan. 20, 1920.

Application filed September 4, 1919. Serial No. 321,508.

To all whom it may concern:

Be it known that I, EDWARD L. CUSHMAN, a citizen of the United States, and a resident of Miami, in the county of Dade and State of Florida, have invented certain new and useful Improvements in Slugs, of which the following is a specification.

My invention is an improvement in matrices for linotype or intertype and similar machines for preventing blurring or smutting of the sheet where several quad lines occur together.

In the drawings:

Figure 1 is a sectional view of the slug; Fig. 2 is a section on line 2-2 of Fig. 1; Fig. 3 is a longitudinal section of a linotype slug embodying the improvement; and Fig. 4 is a plan view of the slug.

As is known in printing where there are several lines of quads occurring together, the sheet is very likely to be blurred or smuttied by its engagement with the surface of the slug.

In the present invention means is provided on the slug for holding the sheet out of contact with the base surface of the slug, that is with the base level from which the formed characters arise. This means is a series of points or raised lines 1 formed on the face of the slug 2 at intervals sufficient to support the sheet between the raised printing surfaces 3. These elevations support the sheet and prevent it bellying against the base surface of the slug where it would become blurred.

The elevations are formed by a suitable depression 4 in the matrix 5 otherwise of usual construction, and they are spaced from each other a distance corresponding to the distance between centers of the raised printing characters.

It will be understood that these elevations 1 are of less height than the raised printing characters 3, so that the said elevations will not be inked, and hence will not print even 45 when they are engaged with the sheet.

I claim:

1. A slug for linotype or intertype machines, having projections raised above the general level of the face of the slug where 50 printing characters are omitted for the purpose specified.

2. A slug for linotype or intertype machines, having projections raised above the general level of the face of the slug where 55 printing characters are omitted for the purpose specified, said projections being of less height than the printing characters and being spaced apart a distance corresponding approximately to the spacing of centers of 60 the printing characters.

3. A slug for linotype or intertype machines, having projections raised above the general level of the face of the slug where 65 printing characters are omitted for the purpose specified, said projections being of less height than the printing characters.

EDWARD LUCIUS CUSHMAN.
